Inventor,
John A. Miller
By Charles J. Schmidt
Atty.

UNITED STATES PATENT OFFICE.

JOHN A. MILLER, OF HOMEWOOD, ILLINOIS.

TRUSS.

Application filed April 23, 1923. Serial No. 638,885.

To all whom it may concern:

Be it known that I, JOHN A. MILLER, a citizen of the United States, and a resident of Homewood, in the county of Cook and State of Illinois, have invented certain new and useful Improvements in Trusses, of which the following is a specification.

My invention relates to trusses of the type disclosed in my Patent No. 1,438,452 of December 12, 1922, in which parallel laminated arch members are spaced apart by web blocks or short lengths of planks. The object of the invention is to procure greater stiffness, rigidity and strength without increasing the weight. In my present arrangement the blocks or short plank lengths of each longitudinal row are displaced longitudinally or spaced apart, but the rows are longitudinally offset so that the blocks of one row will bridge between the blocks of the other row, and at the same time the blocks of one row are interjointed or inter-connected at their ends with the ends of the blocks of the other row so that the blocks form a web chain which of itself forms a strong truss structure and which together with the laminated arch members will form an exceedingly rigid and strong truss which in comparison with its radial thickness may have a very long span and will support heavy loads with safety.

On the accompanying drawing which illustrates my improved construction and arrangement.

Fig. 1 is a side elevational view of a truss.

Fig. 2 is an enlarged side elevational view of a section of the truss, and

Fig. 3 is a sectional view on plane 3—3, Fig. 2.

The truss structure shown comprises the outer and inner arch members *a* and *b* and the web part designated as a whole *c*, the arch parts being parallel. The member *a* is progressively built up of boards 10 to the desired height, the boards being held one against the other by nails 11, the boards breaking joints and overlapping. The inner arch member *b* is formed up in a similar manner of boards 12 held together by nails 13.

The web section of the truss is built up of blocks 14 cut from planks of the desired thickness. The blocks are all of the same shape and are rectangular. The blocks of the upper row are spaced apart and en-

gage with their upper edges against the arch member *a*, while the blocks of the lower row are similarly spaced apart and engage with their lower members against the arch member *b*. The rows are longitudinally offset so that the blocks of one row will bridge the blocks of the other row, and then bolts 15 are extended through the arch members and through the overlapping ends of the blocks, the blocks being set midway between the sides of the arch members with their inner edges in register.

The arch members are usually built up on the ground, suitable template or other guide arrangement being provided so that the arch members will assume their proper curvature. The blocks can be inserted after formation of the arch members or the inner boards of the arch members can first be spiked to the respective blocks and then the other laminations applied until the arch members have been built up. The arch members with the blocks secured thereto are then brought together and the bolts applied.

To strengthen the arch members and blocks against longitudinal displacement and also to increase the bracing effect of the blocks, the blocks are cut away at their inner corners to leave the notches 16, and the tongues 17. When the blocks are assembled the ends of the blocks will engage against the tongues of adjacent blocks and the blocks will be thus positively longitudinally interjointed and inter-connected so that the blocks will form a continuous chain. The blocks thus interconnected and secured transversely by the bolts will of themselves form a rigid truss structure which together with the laminated arch members will form an exceedingly strong truss whose span can be made very long compared with its vertical thickness, and which will sustain heavy loads with great safety.

After formation of the trusses they are set up on suitable supporting pillars 18 of mason work or concrete. The arrangement is particularly adaptable for low buildings such as dance pavilions, skating pavilions, auditoriums or the like where extended floor space is desired without intervening columns and supports. The truss can be inexpensively constructed, stock lumber being used for the arch members, and the blocks can be cut from planks or from odds and ends. When the arch members and blocks are assembled the grain of the wood is parallel with the

truss throughout its extent and this together with the interlinked blocks gives the arch its great strength and rigidity.

I claim as follows:

- 6 1. In a truss structure, the combination of outer and inner arch members and a web structure, said arch members being each built up of laminations and being parallel, the web structure comprising an outer row 10 of blocks and an inner row of blocks, the blocks of each row being spaced apart and the blocks of one row being longitudinally offset from but overlapping the blocks of the other row, and bolts extending transversely 15 through said arch members and the overlapping ends of said blocks.
2. In a truss structure, the combination of outer and inner laminated parallel arch members, a web structure composed of short 20 blocks arranged in outer and inner rows, the blocks of the outer row being spaced apart and those of the inner row being correspondingly spaced apart, the blocks of the outer row abutting against the outer arch 25 member and the blocks of the inner row abutting against the inner arch member, the blocks engaging at their inner edges and those of one row bridging over the spaces between the blocks of the other row, bolts 30 extending transversely through said arch members and the overlapping ends of said blocks, and abutments on said blocks extending into the spaces between associated 35 blocks for locking said blocks against longitudinal displacement.

3. In a truss structure, the combination of an outer arch member and an inner arch member parallel therewith, said members being spaced apart a short distance as compared with their length, web members in the 40 form of short blocks set on edge between the arch members and arranged in outer and inner rows, the blocks of each row being spaced apart and the blocks of one row bridging the spaces between the blocks of the other row, the ends of the blocks being interjointed, and bolts extending transversely 45 through the arch members and through the interjointed ends of said blocks.

4. In a truss structure, the combination 50 of outer and inner laminated arch members, said members being parallel and being spaced apart a short distance as compared with their lengths, a web structure composed of blocks in the form of short lengths of plank, 55 the blocks being set on edge between the arch members and arranged in longitudinal rows, the blocks of each row being spaced apart and the blocks of one row bridging the spaces between the blocks of the other 60 row, each block having an abutment tongue extending between the ends of the blocks which it bridges whereby said blocks will be interjointed, and bolts extending transversely 65 through the arch members and through the interjointed ends of said blocks.

In witness whereof, I hereunto subscribe my name this 17th day of April A. D., 1923.

JOHN A. MILLER.
